UNITED STATES PATENT OFFICE.

EDWIN F. OPIE, OF PHILADELPHIA, PENNSYLVANIA.

AWNING.

967,964.

Specification of Letters Patent. Patented Aug. 23, 1910.

Application filed May 25, 1910. Serial No. 563,344.

To all whom it may concern:

Be it known that I, EDWIN F. OPIE, a citizen of the United States, residing at Philadelphia, in the county of Philadelphia and 5 State of Pennsylvania, have invented certain new and useful Improvements in Awnings, of which the following is a specification.

My invention relates to improvements in 10 awnings, and more particularly to an improved attachment for awnings, the object of the invention being to provide an improved device which will serve to lift the awning when permitted, and which requires 15 a pull on the awning to draw it down where it may be locked in its lowered position.

A further object is to provide a device of 20 this character which may be attached to any ordinary form of awning such as is usually employed on ordinary doors and windows, and which will overcome the necessity for laborious work required in raising awnings, and which will raise the awning quickly and hold it securely.

25 With these and other objects in view, the invention consists in certain novel features of construction and combinations and arrangements of parts as will be more fully hereinafter described and pointed out in the 30 claims.

In the accompanying drawings: Figure 1, is a perspective view illustrating my improvements. Fig. 2, is an enlarged view in side elevation of one of the attachments. 35 Fig. 3, is a view in longitudinal section thereof. Fig. 4, is a plan view, and Fig. 5, is a view in transverse section.

1, represents the rod frame, and 2, 2, my improved attachments to which the awning 40 ends of the rod frame 1 are connected, as will more fully hereinafter appear. These attachments 2 are secured to the window frame, support the ends of the rod frame 1, and serve to pivot the frame 1 and move it 45 to a vertical position when permitted. The awning 3 is illustrated in dotted lines, and is secured at its upper end to the window frame, and at its lower open end is secured to the rod frame 1, and the arms of which 50 latter are secured in the pivoted arms 4 of my improved attachments, which will now be described and as I employ two of these attachments and they are both alike, the description of one will apply alike to both.

55 5, represents a casing which is preferably a casting having a base plate 6, and this

base plate and the webs of the casting are provided with openings 7 for the reception of screws 8 to secure the device in place. These openings 7 are provided so that the 60 screws may be driven into the frame from either direction, so that the attachment may be secured in the most convenient manner.

A tube 9 is mounted to slide in casing 1, and a coiled spring 10 is located in this 65 tube, bears at its inner end against the base 6, and at its outer end against a screw-threaded plug 11 screwed into the outer end of the tube 9, so that the tension of the spring may be readily adjusted, or the 70 spring removed and replaced. The tube 9 on one side is provided with a series of teeth forming a rack 12, which engage the teeth of a segmental pinion 13, integral with the arm 4 above mentioned. This segment 13 and the arm are preferably hollow, so as to accommodate the arm of frame 1. The arm 4 is pivoted on a journal bolt 14, extending through registering openings in the casting 5, and segment 13. This journal bolt 14 is also adapted to be projected through the opening 15 in the end of the frame arm and said journal bolt is preferably secured by a cotter pin 16. The arm of frame 1 is further confined in the hollow 80 arm 4 by means of cross pins 17 above and below the same and secured in registering openings in the arm 4 by means of cotter pins 18. To hold the arm 4 in its horizontal position with the spring 10, compressed, a catch 20 is pivoted on the arm 4 and is adapted to engage in a notch 21 in casting 5, and this catch is preferably provided with an arm 22 of some length to facilitate its manipulation.

95 The operation is as follows: When the awning is down as illustrated in Fig. 1, the spring 10 is under tension and the catch 20 holds the arm 4 and the awning frame from being moved upward by the spring. When 100 it is desired to raise the awning, the operator moves the catches 20 out of the notches 21, when the springs 10 will force the tube 9 outward, and due to the rack and pinion engagement between said tubes and the arms 105 4, the inner frame with its awning will be swung up out of the way. Some mechanism, (not shown) would of course be provided for pulling the awning down into lowered position, but it may be found in a 110 good many instances that no additional means is necessary, as the awning can prob-

ably be drawn down by simply pressing against the frame 1.

Various slight changes might be made in the general form and arrangement of parts described without departing from my invention, and hence I do not limit myself to the precise details set forth, but consider myself at liberty to make such changes and alterations as fairly fall within the spirit and scope of the appended claims.

Having thus described my invention, what I claim as new and desire to secure by Letters Patent is:

15. 1. A device of the character described, comprising a casting, an arm pivoted to the casting, a longitudinally movable rack, a pinion on the arm engaging the rack, and a spring pressing against said rack, substantially as described.
20. 2. A device of the character described, comprising a casting, an arm pivotally connected to the casting, a segmental pinion on said arm, a tube mounted to move longitudinally in the casting, a rack on the tube engaging the pinion, and a coiled spring within the tube tending to move the same longitudinally, substantially as described.
25. 3. A device of the character described, comprising a casting, an arm pivotally con-

nected to the casting, a segmental pinion on 30 said arm, a tube mounted to move longitudinally in the casting, a rack on the tube engaging the pinion, said tube having internal screw threads in its outer end, and a screw-threaded plug screwed into said tube 35 and engaging the spring, substantially as described.

4. A device of the character described, comprising a casting, an arm pivotally connected to the casting, a segmental pinion on 40 said arm; a tube mounted to move longitudinally in the casting, a rack on the tube engaging the pinion, said tube having internal screw threads in its outer end, a screw-threaded plug screwed into said tube 45 and engaging the spring, said casting having a notch therein, and a catch on said arm constructed to engage in said notch and hold the arm in position against the tension of the spring, substantially as de- 50 scribed.

In testimony whereof I have signed my name to this specification in the presence of two subscribing witnesses.

EDWIN F. OPIE.
